UNITED STATES PATENT OFFICE.

SOLOMON M. CUTTER, OF WETHERSFIELD, CONNECTICUT, ASSIGNOR TO CAPEWELL HORSE NAIL COMPANY, OF HARTFORD, CONNECTICUT, A CORPORATION OF CONNECTICUT.

PREPARATION OF CONTINUOUS METAL ROD.

1,285,057.

Specification of Letters Patent. Patented Nov. 19, 1918.

Application filed May 5, 1917, Serial No. 166,528. Renewed September 3, 1918. Serial No. 252,467.

To all whom it may concern:

Be it known that I, SOLOMON M. CUTTER, a United States citizen, residing at Wethersfield, Connecticut, have invented the following-described Improvements in the Preparation of Continuous Metal Rod.

The invention comprises a method and apparatus for preparing and cleaning continuous rod or wire stock in preparation for subsequent mechanical treatment, as for example, the drawing thereof in the manufacture of nails, tacks, wire, etc., and its principal object is the elimination of the apparatus and time involved in pickling the rod and thereafter baking it as now commonly practised and considered essential and to produce an equally clean and bright surface on the metal by mechanical action only and with a minimum expenditure for equipment and power. This principal object is attained by continuous operation and in the same operation with the annealing of the stock, which is also continuously performed, and it may also be combined with the first reduction of the sectional area of the stock, thereby further simplifying and reducing the cost of manufacture by saving the expense involved in repeated handlings of the same material.

30 The accompanying drawings illustrate the manner of carrying on the new process and certain principal or desirable features of the apparatus employed.

Figure 1 represents in diagram the course of the rod stock from the condition in which received from the rolling mill, through the successive operations constituting the preferred form of this invention, to its final condition ready for the manufacture of 40 nails or wire;

Figs. 2 and 3 represent in elevation and plan respectively, the rod-cleaning or scale-removing part of the invention; and

Fig. 4 is a cross section on larger scale of 45 the cleaning chest and the sand blast apparatus.

Fig. 5 is a modification.

The coil of crude rod or wire is placed on the reel table 1 (Fig. 1) and led therefrom 50 through or alongside of an electric welder or other joining device 2 whereby the ends of successive coils of stock can be joined into a continuous length for passage through the apparatus. This welder does not of itself 55 form part of the invention, being well

known to the electric welding art, and it may be understood as representing any suitable means of joining the stock. From the welder the stock is led directly between the opposing spring-pressed roller electrodes 3 60 of an electric annealing apparatus 4 where it becomes interposed in the circuit of a suitable current which, traversing the rod crosswise and while in motion, promptly raises it to the red heat necessary for annealing it. Depending upon the size and material of the rod and its velocity, the electric annealer may comprise one or many pairs of opposing electrodes distributed along the path of the stock and supplied 70 with current of appropriate character for the purpose stated. Its specific mode of operation is subject to adaptation to the material to be annealed in various ways which will be well understood. In respect to the 75 broadest aspect of my process the said device may be considered as representing any suitable means of intensely heating the stock while in transit. From the annealer the heated stock travels directly through a 80 down-turned tube or conduit 5 into a bath of molten lead or other metal or material of moderately low fusing point, lower than the annealing heat. The tube 5 is preferably closed at its lower end by the molten 85 bath and designed to protect the rod, so far as possible from oxidizing contact with the air. The molten bath is contained in a trough 6 of greater or less length, depending on the velocity and thickness of the 90 stock, and is kept in its molten state by means of gas burners 7 distributed beneath it. The function of the molten metal is to provide or permit the cooling of the stock at the gradual rate necessary for proper annealing and while out of contact with the atmosphere so as to minimize the production of scale. For this purpose the trough 95 may consist of one continuous receptacle or a series of receptacles as shown in Fig. 5 100 each containing a bath of successively lower temperature with curved tube conductors 5^a between them for guiding the stock from each one to the next. It will be readily understood that by means of an adequate number of these receptacles, the continuous stock traveling therethrough will be subjected to the proper temperature gradient for the best annealing results and will be the least 105 subject to scale-forming conditions during 110

the heat treatment. The material constituting the bath or baths may be lead, as above stated, or the low-fusing lead alloys which will be protected by an adequate flux 5 to guard against their own oxidation, or for the lower temperatures certain mineral oils may be used. In the case of a single, long trough the temperature may be made higher at the receiving than at the delivery end 10 by control of the burners.

Notwithstanding any precautions some scale will be formed, though by no means so much as in the case of furnace annealing and air-cooling and some scale and undesirable dirt is ordinarily found on the crude stock prior to annealing. For removing such scale, and in place of the common pickling process, the continuous annealed stock from the trough 6 is led through a bench of straightening rolls 8, which, in the present case are driven solely by their contact with the stock, to a bending device which may be called the scaler since its function is solely that of removing or loosening the dirt and scale, which is accomplished by bending and reversely bending the stock on short radii. This device comprises two rolls 9 and 10 appropriately journaled in a suitable framework, geared together by the gears 11 and 20 driven by the large gear 12 and sprocket chain 13 or in any other suitable way and at a certain speed later referred to. The roll 9 first encountered by the stock, is disposed in advance of the other roll 10 and 25 slightly higher than that roll so that the stock will run straight to the first roll and wrap around it for about half its circumference, running thence to the second roll 10, wrapping around that roll also about 30 one-half its circumference. The diameter of each roll is small enough so that the bending of the stock around its half circumference, first in one direction and then in the other, will so distort it as to dislodge or at 35 least loosen the scale and dirt; in the case of stock for use in making horse-nails, the diameter is approximately four inches. It has long been customary to loosen the scale on metal rod by bending it back and forth 40 and the scaler above described utilizes that well understood expedient but carries it on to a greater extent than heretofore practised within my knowledge, by bending the stock at least 180° in each direction and on a short 45 radius as above stated. The scaler rolls are provided with flanges 14 on one or both sides of the stock and which, by abrasion on the sides of the stock, assist in dislodging much of the loosened scale.

50 From the scaler the stock passes directly to the cleaner mechanism which is comprised of two departments of different degrees of cleaning effectiveness, to wit, a steam blast apparatus represented by the steam jet nozzles 15, and a sand blast apparatus inclosed

in a chamber or chest 16. For crude stock which is not particularly dirty or heavily scaled in the first instance, I have discovered that the loosening of such scale as effected by the scaler above described, sufficiently 55 weakens its attachment to the metal to permit of its removal by steam jet blast alone which is of course a far more economical treatment than any part of the common pickling operation. For this purpose the stock 60 from the scaler rolls 9 and 10 runs through the sand blast chamber 16, while the same is inoperative, to the outlet in the wall at the far side of the chest at which point the steam jet nozzles 15 direct powerful and 65 very high velocity jets of steam convergently and on opposite sides of the stock and in such manner that the steam blows back through the outlet into the chest 16 wherein it is condensed and removed as water or 70 finds other escape. In the case of square or rectangular stock, as in horse-nail stock, the jets deliver to the opposite corners thereby covering all four sides but any number of jets may be employed. A steam pressure of 60 to 100 pounds escaping through 75 jet holes about $\frac{1}{8}$ inch diameter in this manner will effectually scour and clean the general run of iron or low carbon steel rod used in horse-nails if it has previously been 80 passed through a scaler of the kind herein described.

For specially dirty rod stock, however, the sand blast apparatus is additionally brought 85 into operation and when it is used the steam jets are continued and serve the additional purpose of removing the sand from the issuing rod and blowing it back into the chest. It is important that no sand be left on the 90 rod to injure the drawing dies in later stages 95 of manufacture.

The sand blast comprises a set of high 100 velocity ejector nozzles 17 disposed within the chest to attack all sides of the stock, as shown in Fig. 4, and each is operated by steam or other fluid pressure medium taken 105 from the same main, 18, which supplies the jet nozzles 15. The entire set of sand blast nozzles is controlled by the shut-off valve 19 as indicated. The blast nozzles 17 are constructed on the usual ejector principle and draw their supplies of sand from the bottom 110 of the chest, through the sand pipes 20. The sand is ordinarily mixed with the water 115 from steam condensation which is kept at a predetermined level in the chest by an appropriate overflow connection 21 (Fig. 4). The action of the apparatus will be understood from the drawings without further detailed description and it will be apparent 120 that the combined action of the sand blast and jet nozzles 15, acting on the rod from the scaler rolls 9 and 10 will produce a bright clean surface on the dirtiest stock, equal if not superior to the best that can be 125 130

obtained by pickling, washing and baking, and is of course produced by continuous operation besides being infinitely cheaper to carry on. It will be understood however 5 that the use of the sand blast is auxiliary to the essential steps which comprise the use of the scaler and the jets of steam, and is to be used only in the case of extraordinary tenaciousness of the surface material to the 10 latter. As above stated, the general run of crude stock as received from the rolling mill is of such a character as to be thoroughly cleaned by the use of the scaler and the jets alone.

15 In my prior Patents No. 1202368 and No. 1142499, I have disclosed the utilization of a sand blast for cleaning rod in substitution for pickling and in the first mentioned patent the combined use of the sand blast with coincident distortion of the rod by twisting. While these methods are entirely suitable for the purposes set forth in those patents, my present invention is to be distinguished from them by several highly important particulars. The bulk of the removed scale is 20 removed at and by the scaler rolls where it falls to the floor or in a receptacle and is in a condition to be salvaged and brings a good price on the market. It is not valuable when mixed with sand as in the case of both of the mentioned patents. The output of the present process is greater, since the velocity of the stock through the scaler and jets may be higher and at the same time 25 the expense, due to the saving of steam, is materially reduced. Even when the sand blast is in action less abrasive effect is required of it and hence less steam is used, than in the case of the said patents. Other 30 distinctions and improvements from the manufacturing and mechanical point of view will be apparent to those skilled in this art.

The stock is drawn through the sand blast 45 chest and jet nozzles by a powerful winding drum 22 on which it is coiled in its cleansed condition and from which it may be removed in coil form to be transported direct to the drawing or finishing machines. 50 The detail of the winding drum is quite old in the art and need not be described. It is driven by a belt pulley 23 which also drives the sprocket 24 of the chain 13 above referred to as driving the scaler roll. The 55 speed ratio of the sprockets 12 and 24 is such as to give the scaler rolls a very slightly higher surface velocity than that which is imparted to the stock by the winding drum. By this speed relation the scaler rolls assist 60 in drawing the stock through the apparatus which precedes it in the present system and at the same time the said rolls become more effective in their scale removing function. This is because their tendency is constantly 65 to produce a slackened condition in the

stretch of stock extending forwardly from them which however merely results in a certain amount of slippage on the stock because the said rolls have no grip thereon other than by the friction upon their half 70 circumferences and the production of the slightest slack relieves such friction to the point of slippage. Such slippage or rubbing friction is found to be highly beneficial in loosening tough scale for subsequent removal by the steam jets or the sand blast as the case may be.

Between the winding drum and the jets, the stock already cleaned by the mechanism above described is subjected to a first drawing operation by which it is reduced to a predetermined and uniform cross-sectional size. Such apparatus is of common design and in the present case is represented by two pairs of drawing rolls 25 mounted on 80 axes which are at 90° angles from each other to form between the rolls a pass of the requisite size. Thus the coil of rod eventually removed from the winding drum is not only cleaned equivalent to a pickled rod but is 85 also uniformly sized to the requisite standard gage and all of the said preparation is done rapidly and continuously and the apparatus required for such preparation occupies less space and consumes less power 90 than the ordinary procedure and less than necessary with my prior patents for producing equivalent results.

It will be of course understood that the preparing process is not confined to the use 100 of all the detailed steps above described and that various omissions, additions, modifications, reversals, and changes of proportion may be resorted to within the scope of the following claims.

105 Claims:

1. The process of preparing rod stock for manufacture, in lieu of pickling the same, which consists in first passing the stock through a scaler wherein it is continuously 110 bent and reversely bent and subjected to rubbing friction and then through the action of high velocity fluid pressure jets.

2. The process of preparing rod stock for manufacture, which consists in continuously 115 bending the stock in opposite directions around substantially one-half the circumference of each of two adjacent bending rolls thereby dislodging the bulk of the scale therefrom and then subjecting the stock continuously to the action of high velocity fluid pressure jets.

3. The process of preparing rod stock for manufacture, which consists in first continuously bending and reversely bending the 120 stock to dislodge the bulk of the scale therefrom and thereafter subjecting it to fluid pressure jets containing an abradant material.

4. The process of preparing rod stock for 125

manufacture, which consists in first removing some of the scale therefrom by bending the stock, then subjecting it to the action of fluid pressure jets successively with and 5 without abradant material therein.

5. The process of preparing rod stock for manufacture, which consists in passing a continuous length thereof successively and continuously through an annealing heat and 10 a cooling medium and through a scale removing and cleaning apparatus.

6. The process of preparing rod stock for manufacture, which consists in passing a continuous length thereof successively and 15 continuously through an annealing heat and cooling medium, a scale-removing and cleaning apparatus and a set of sizing drawing dies.

7. The process of preparing rod stock for 20 manufacture, which consists in locally raising a continuous, traveling length of the stock to an annealing temperature, cooling the same as it emerges from the annealing zone and while passing it through a non- 25 oxidizing medium, and coincidentally cleaning the stock emerging from said medium.

8. Apparatus for preparing rod stock for manufacture comprising means for advancing the stock, a scaler comprising a pair of 30 bending rolls acting thereon and each engaged with opposite sides thereof and means for driving the bending rolls at a different surface velocity from that of the stock engaged therewith.

9. Apparatus for preparing rod stock for 35 manufacture, comprising means for advancing the stock, a scaler comprising a pair of bending rolls acting thereon and each engaged with opposite sides thereof, means for driving the bending rolls at a different surface velocity from that of the stock engaged thereby and fluid pressure jets acting on 40 said stock subsequent to the bending thereof.

10. Apparatus for preparing rod stock for manufacture, comprising means for advancing 45 the stock in combination with a scaler including a pair of bending rolls, a sand blast chest receiving the stock from said rolls, and pressure jets of non-abrading material acting on said stock and adapted to 50 blow the scale and dirt therefrom into said chest.

11. Apparatus for preparing rod stock for manufacture, comprising the combination of a scaler including a pair of bending rolls, a 55 sand blast chest receiving the stock therefrom and pressure jets of non-abrading fluid acting on the stock issuing from the said chest.

12. Apparatus for preparing rod stock for 60 manufacture, comprising means for advancing the stock, a pair of adjacent rolls about which the stock is bent and reversely bent, and flanges adjacent said rolls with which the stock engages for the purpose set forth. 65

In testimony whereof, I have signed this specification.

SOLOMON M. CUTTER.
